UNITED STATES PATENT OFFICE.

RAY E. STAMBAUGH, OF SHERIDAN, WYOMING.

TABLE.

1,377,102.

Specification of Letters Patent.

Patented May 3, 1921.

Application filed July 2, 1920. Serial No. 393,539.

To all whom it may concern:

Be it known that I, RAY E. STAMBAUGH, a citizen of United States, residing at Sheridan, in the county of Sheridan and State of Wyoming, have invented new and useful Improvements in Tables, of which the following is a specification.

This invention comprehends the provision of a table which can be varied in size by detachably connecting together a plurality of identically constructed sections, the component parts of each section being susceptible of being compactly folded to reduce its size when not in use.

The nature and advantages of the invention will be better understood when the following detail description is taken in connection with the accompanying drawings, the invention residing in the construction, combination and arrangement of parts as claimed.

In the drawings forming part of this application like numerals of reference indicate similar parts in the several views and wherein:

Figure 1 is a top plan view of the table.

Fig. 2 is a side elevation of one of the table sections.

Fig. 3 is an end elevation.

Fig. 4 is a view in elevation of one of the sections folded.

Fig. 5 is an edge elevation showing one of the sections folded.

Fig. 6 is a detail sectional view taken through one of the table sections.

Referring to the drawings in detail and particularly Fig. 1, the table constructed in accordance with my invention may be varied in size by detachably connecting together any number of sections indicated at A. Each of these sections is identical in construction, and the illustration and detail description of one will suffice.

Each section A of the table comprises a top and a supporting structure therefor, the top being divided into halves, each half being indicated at 10 and hingedly connected together as at 11. The combined area of these halves may be varied, and the table may be constructed from any suitable material without departing from the spirit of the invention. The top is supported by spaced pairs of divergently disposed members 12, the corresponding lower extremities of these members being hingedly secured to a connecting bar 13 which is ar-

ranged beneath the table in a line with the hinged joint 11. The connecting bar 13 is substantially co-extensive in length with the section. The corresponding upper extremities of the diverging members 12 bear against the under side of the halves 10 of the table top but are not connected therewith. Secured to the under side of each half 10 of the top, for each member 12, is one leaf 14 of a hinge, the other leaf 15 supporting a collar 16 through which the adjacent member 12 slides. The members 12 at each side of the section are connected in pairs by diagonally disposed braces 17 which intersect and are connected together at a point midway of their ends as at 18.

Associated with the divergently disposed members 12 at each end of the table section is a pair of supporting legs 19 which are convergently disposed as shown in Fig. 3 and have their upper ends arranged to bear against the members 12 with which they are associated but are not connected with the latter. The legs 19 are slideable through collars 20, each of which is supported by links 21 pivotally associated with the pintle 22 of the hinge connecting the divergent members 12 with the connecting bar 13 therefor. Also connected with each collar 20 and pivotally associated with the adjacent leg 19 is the section 23 of a rule joint, the cooperating section 24 thereof being pivotally associated with the adjacent member 12. When the sections 23 and 24 respectively are operatively associated, the legs 19 are held fixed relatively to the pair of diverging members 12 with which they are associated to properly and rigidly support the table section in position for use. Pivoted to the under side of one of the halves 10 of the table top is a bar 25 which is adapted to be swung to a position to bridge the joint between the halves 10 of said top to increase the strength and rigidity of the latter, the bar 25 having its free end engaged by a suitable fastening means indicated at 26 for holding the bar in position for use, the fastening means 26 being carried by the under side of the other half 10 of said top.

Secured to the under side of each half 10 of the table top is a sliding bolt 27 arranged to be projected beyond the opposite ends of the table section for association with a keeper (not shown), but of any suitable character carried by the meeting end

of the adjacent section of the table. A similar bolt 28 is carried by one end of the connecting bar 13 for association with a suitable keeper (not shown) carried by the 5 meeting end of the connecting bar of the adjacent table section. Also projecting from the same end of each half 10 of the table from which the bolts 27 project is a plate 29 which bridges the joint between the 10 meeting ends of the adjacent sections, a similar plate 30 for the same purpose projecting from the connecting bar 13 at the end with which the sliding bolt 29 is associated. Each supporting leg 19 is suitably 15 braced by a member 31 hingedly connected as at 32 with the leg 19 adjacent its lower end, the member 31 being diagonally disposed and having its opposite end hingedly connected as at 33 with the adjacent member 12 of the next pair of these members as 20 shown in Fig. 2. It will be noted that the hinged joints 32 and 33 respectively of the bracing member 31 are arranged in planes which allow the legs together with the members 31 to be folded.

In practice, a table of any desired size can be produced by utilizing the requisite number of table sections, the sections being arranged end to end and having their meeting ends suitably connected together by means of the bolts 27 and 28 respectively. When the sections are arranged for use, the tops thereof are braced by the bar 25 which bridges the hinged joint between the halves 35 of the top, while rigidity is afforded the supporting structure by means of the sections 23 and 24 of the ruled joint which interlock as at 20'. By reason of the construction shown and described it is manifest that 40 the component parts of each table section can be folded so that the size of each section can be reduced to a minimum. For this purpose it is only necessary to break the joint between the sections 23 and 24, and 45 to throw the bar 25 to an inactive position wholly to one side of the hinged joint 11 of the top. The halves 10 of the top can then be moved into face to face contact, bringing the hinged joint 11 in close proximity to the connecting bar 13. During this 50 operation, the members 12 of each pair slide through their respective collars 16 to lie in parallelism with the halves 10 of the top with which they are associated. The hinged 55 connection 22 between the members 12 and the connecting bar 13, and the hinged connection between the members 12 and the top, allow the divergently disposed members to assume the position mentioned when 60 folded. The supporting legs 19 together with their members 31 are swung upon their hinged joints to assume positions substantially parallel with the members 12, as indicated in Fig. 5. The construction is such 65 that it can be readily and easily collapsed

to occupy a minimum of space when not in use, and can be just as easily and quickly set up in position for use when the occasion requires.

While it is believed that from the foregoing description the nature and advantages of the invention will be readily apparent, I desire to have it understood that I do not limit myself in this connection, and that such changes may be resorted to when desired as fall within the scope of what is claimed.

What I claim is:

1. A table section including hingedly connected top sections, divergently disposed supporting members arranged beneath said sections, a connecting bar coextensive in length with said top, and hingedly connected with the lower corresponding extremities of said diverging members, means for associating the upper end of said members with said sections for sliding movement with relation thereto, a keeper carried by one of said sections, a fastening bar pivotally connected with the other section to engage the keeper when bridging the joint between said sections, and supporting legs associated with said members and susceptible of being folded in a substantially parallel position therewith. 95

2. A table section comprising a top made up of two hingedly connected sections, divergently disposed supporting members arranged beneath said sections, a connecting bar interposed between the lower corresponding extremities of said members, and hingedly connected thereto, the hinge having one leaf secured to the underside of each section, a collar carried by the other leaf of the hinge and slidably receiving the adjacent member, whereby the said members are held associated with the top sections for sliding movement with relation thereto, and supporting legs connected with said members and capable of being folded in parallel position therewith with respect thereto. 100

3. A table section comprising a top made up of two hingedly connected sections, divergently disposed supporting members arranged beneath the sections and having their upper ends associated with the top for sliding movement with respect thereto, the lower extremities of said members being spaced, a connecting bar arranged between said extremities and hingedly connected therewith, convergently disposed supporting legs pivotally connected with said members and adapted to be folded in a plane parallel therewith, links pivotally associated with the hinge connecting the said members with the said bar, sleeves carried by said links and slidably receiving said supporting legs as and for the purpose specified. 115 120 125 130

4. A table section comprising a top made up of two hingedly connected sections, divergently disposed supporting members arranged beneath the sections, a connecting bar interposed between the lower corresponding extremities of said members and hingedly connected thereto, means for associating the opposite ends of said members with the table sections whereby said members are permitted sliding movement with

respect to the top, diagonally disposed braces connecting the corresponding members of the respective pairs, supporting legs, and means pivotally connecting the legs with said members whereby said legs may 15 be folded in a plane parallel with the members.

In testimony whereof I affix my signature.

RAY E. STAMBAUGH.
